UNITED STATES PATENT OFFICE.

GEORGE S. MONSON, OF ST. PAUL, MINNESOTA.

DENTAL IMPRESSION TRAY.

Application filed July 31, 1920. Serial No. 400,325.

To all whom it may concern:

Be it known that I, GEORGE S. MONSON, a citizen of the United States, resident of St. Paul, county of Ramsey, State of Minnesota, have invented certain new and useful Improvements in a Dental Impression Tray, of which the following is a specification.

In the practice of dentistry, it is customary to provide a tray having a concave surface on one side and a handle or finger grip by means of which the tray is inserted into the mouth. The concave surface is adapted to receive a plastic material which is forced against the roof of the mouth by the pressure of the tray for the purpose of making an exact reproduction of the roof of the mouth in the plastic, from which reproduction a plate for use with artificial teeth is manufactured.

It is essential in taking this impression that the tray be held evenly and a uniform pressure be exerted thereon in the lines of stress that ultimately the dentures will be forced to assume in the act of mastication. Unless this is done, the tray is apt to tilt or turn in the fingers, resulting in an accurate impression being taken of the roof of the mouth and consequently a poor fit for the plate when it is made.

The object of my invention is to provide means in connection with the tray which will insure a uniform upward pressure thereof and in consequence a perfect reproduction or impression of the roof of the mouth in the plastic contained in the tray.

The invention consists generally in various constructions and combinations, all as hereinafter described and particularly pointed out in the claims.

In the accompanying drawings forming part of this specification.

Figure 1 is a top view of a tray embodying my invention,

Figure 2 is a bottom view of the same,

Figure 3 is a sectional view on the line 3—3 of Figure 1 showing the depth and position of the finger or thumb grip therein.

In the drawing, 2 represents the tray of the usual size and shape, made preferably of metal, having a concave upper face 3 with a centrally arranged raised or arch por-

tion 4. This face is filled with a suitable plastic material in which the reproduction or impression of the roof of the mouth is formed. On the underside and projecting from one end of the tray is a short handle 5, usually found on devices of this kind. This handle is grasped by the user of the device and the tray held in the roof of the mouth and forced upwardly to make the 60 desired impression in the plastic. To insure the accurate seating of the tray and a uniform upward pressure thereon at all points, I provide on the underside a finger seat such as a thumb or finger impression 65 6 having a concave surface 7 which forms a continuation of the under surface of the handle and enclosed by a rib or flange 8 which serves to hold the thumb or finger in the depression of the grip and insure its 70 accurate seating therein and a uniform pressure at all points on the walls of the tray. I have found from actual practice that an impression can be made with this device very quickly and with far more accurate 75 results than has been found to be possible in trays of this kind as ordinarily made.

The finger or thumb grip may be formed in any suitable way in the bottom of the tray, it being essential of course, that it be 80 in line with the center of the handle and opposite the center of the impression surface of the tray.

I claim as my invention:

1. A dental impression tray having a 85 concave upper surface with a centrally arranged raised portion and adapted to receive a plastic material in which the impression of the roof of the mouth is formed, one end of said tray having a handle on the 90 underside thereof and the under surface of said tray having a concave finger seat at the end of said handle and forming substantially a continuation of the surface thereof, said finger seat being adapted to 95 receive the thumb or finger and insure uniform upward pressure at all points on the walls of the tray.

2. A dental tray, including a tray and a handle therefor, and said tray having its 100 under face inward of the handle provided with a depression forming a finger hold.

3. A dental tray having a concavity on its under face whose sides and outer walls are surrounded by flanges.

4. A dental tray having a concavity on its under face adjacent to its rear which gradually increases in depth from its outer to its inner end, its said inner end being

rounded and its sides being also slightly rounded upwardly and outwardly, a continuous flange surrounding the sides and 10 the said inner end.

In witness whereof I have hereunto set my hand this 26th day of July, 1920.

GEORGE S. MONSON.
